UNITED STATES PATENT OFFICE.

ALBAN W. ANDERSON, OF BLOOMINGTON, ILLINOIS.

ROTARY-GAS-VALVE CASE.

Application filed March 25, 1927. Serial No. 178,368.

This invention relates to rotary valves for internal combustion engines and more particularly to rotary valves simultaneously serving a plurality of cylinders of an engine 5 of the four cycle type.

Such valves necessarily include a housing structure within which the valve rotates and in devices of this character with which I am familiar, this wall being isolated from the 10 heat of the exhaust gases controlled by the valve is not so highly heated as the valve, with the result that there is a tendency to unequal expansion which is attended by sticking and scoring of the valve. Accordingly, 15 an important object of the invention is to provide a housing structure for supporting the valve in which the housing is subjected to temperatures similar to those to which the valve is subjected, so that a substantially 20 equal expansion will result and there will be no binding or scoring.

A further and more specific object of the invention is to provide a structure such that the exhaust gases may be circulated about the housing in controllable quantities so that this housing is heated with a controllable 25 heat to maintain the even temperature above referred to.

A still further object of the invention is to provide a construction such that the period during which the exhaust gas remains in the valve proper is materially reduced, so that there is not so much tendency to high-heating of the valve and, at the same time, a construction is provided whereby the incoming 35 gas which is relatively cool and has a refrigerating effect may serve to cool the valve and further reduce the heating thereof.

These and other objects I attain by the 40 construction shown in the accompanying drawings, wherein for the purpose of illustration is shown a preferred embodiment of my invention and wherein:—

Figure 1 is a vertical transverse sectional view through an engine embodying rotary valve mechanism constructed in accordance with my invention;

Figure 2 is a plan of the rotary valve element removed;

Figure 3 is a section on the line 3—3 of Figure 1;

Figure 4 is a section on the line 4—4 of Figure 1;

Figure 5 is a top plan view of the valve case;

Figure 6 is a view similar to that of Fig-

ure 4, the valve element being removed and a slightly modified case construction illustrated.

Referring now more particularly to the drawings, in which, for the purpose of illustration, I have shown an L-head engine, this engine includes the usual oil base 4, crank case 5, cylinder block 6, and head 7. Within the cylinder operates the usual piston 8. The space 9 above each cylinder within the head is provided with an outlet port 63. A valve case 12 at present shown as secured to the head by bolts 13 extends beneath the overhang of the head and is provided with ports 35 aligning with the ports 63 of the head. Arranged within the case is a valve housing 34 connected with the case by the walls 36 of the ports 35, these ports 35 opening to the interior of the housing. 75

At opposite sides of its longitudinal center, the housing is further connected with the case by the walls 38 of the inlet ports 37 which, through manifolds 62, may be connected with a source of explosive mixture. 80 The case is still further connected to the housing by the walls 46 of oil ports 45 which are distributed longitudinally of the housing structure and at the exterior of the case are in communication with an oil feed 85 conduit 44 which may be supplied from any suitable source. In all constructions, the case 12 will be provided intermediate the ends thereof with an exhaust port 52. In Figure 1, this exhaust port is shown as communicating directly with the exhaust manifold, while in Figures 4 and 6, the communication is controlled by a damper. In the construction of Figure 4, the damper 57 is imperforate while in Figure 6, the damper 95 58 is formed with an opening 59. In either situation, the damper employed may be either perforate or imperforate, depending upon the particular engine or type of engine with which it is employed. At one end, the 100 case is provided with an exhaust port 51 preferably controlled by a damper 54 illustrated in Figures 4 and 5, although this damper may be omitted, as illustrated in Figure 3, if desired. As at present disclosed, the port 51 is formed in a head 51^a 105 for one end of the casing 12 and adapted for connection with the exhaust manifold. In the modification illustrated in Figure 6, a damper 55 is employed having a perforation 56 to control the passage of exhaust 110 gases. Optionally, the housing may be pro-

vided in its side wall adjacent its opposite end with a further exhaust outlet 53, as disclosed in Figure 6. This exhaust outlet will be controlled by a damper 60 having an aperture 61.

The exhaust valve designated at 21 is in the form of a tube, one end of which is closed and has applied thereto a gear 20. This tube has longitudinally spaced series of port openings, of which the ports 28 and 29 are circumferentially spaced. The ports 28 constitute intake ports and are in communication with the intake ports 37 of the housing through the ports 27 in the valve wall which align with the ports 37. The ports 29 are in communication with a conduit 22 or 23 which is concentric with the valve wall and has passages connecting with each of the ports. In the present illustration, where a six cylinder engine is employed, the conduits 22 and 23 each take care of the exhaust of three cylinders at one end of the engine and each communicate at their inner ends with one of the ports 29 on opposite sides of the transverse medial line of the valve. From this point, they extend to the end of the valve structure and the conduit 22 opens directly through the end wall. The conduit 23 which terminates at the closed end of the valve is provided with an annular port 31 opening through the side wall of the valve beyond the end of the housing 34. It will be obvious that the exhaust from the three front cylinders will pass through the conduit 23 and out through the port 31 to the space 32 between the valve case and valve housing. If the outlet 53 is not employed, all of this gas must pass rearwardly to the outlet 52 and in its passage, move about the exterior of the housing 34 to heat the same. All of the gases from the rear three cylinders pass through the conduit 22 through the rear end of the valve to escape by the port 51. If the port 51 restricts the flow of these gases or the flow of these gases is restricted by the damper 54 or 55, a portion or all of these gases must return through the space 32 to the port 52.

In the use of the device, assuming only the exhaust ports 51 and 52 are employed in the valve case, regulation of the dampers is resorted to until expansion of the case 34 at different speeds of the engine is the same as that of the valve, after which the dampers are fixed. The same process is followed where the three exhaust ports 51, 52 and 53 are employed. It will be obvious that with the latter construction, the amount of gas passing through the opening 52 may range anywhere from zero to the entire exhaust of all of the cylinders and by this structure, a particularly fine graduation of the degree of heat to which the case is subjected may be had. Regulation of these dampers is preferably accomplished by sim-

ply substituting one damper element for another until the proper relation of the openings has been determined. Once this has been determined, the damper elements may be employed as fixtures and there is no necessity for adjustment thereof during operation of the engine.

It will also be obvious that with the construction employed, the incoming gases pass about the conduits 22 and 23 and are heated thereby. In absorbing heat from these conduits, the conduits are cooled so that the valve will not be heated to an excessive degree and thus prevent heating of the case to such an extent, that, between the heat of the valve and the case, injected lubricant will be charred and destroyed. Operation of the valve may be effected from the crank shaft in any suitable manner. In the present instance, the crank shaft 14 is connected with the valve through timing gearing 15 and 16, by means of which a driving chain 19 is actuated.

Since the construction employed is obviously capable of a certain range of change and modification to adapt the same to different types of engines without in any manner departing from the spirit of the invention, I do not limit myself to such specific structure except as hereinafter claimed.

I claim:—

1. In rotary valve mechanism for internal combustion engines, a case, a housing within and supported from and in spaced relation to the case, a valve rotatable in the housing having intake and exhaust ports, connections between the exhaust ports conducting exhaust gases passing therethrough to the ends of the housing and into the space between the case and housing, the case having an exhaust port leading therefrom at a point intermediate the ends of the housing.

2. In rotary valve mechanism for internal combustion engines, a case, a housing within and supported from and in spaced relation to the case, a valve rotatable in the housing having intake and exhaust ports, connections between the exhaust ports conducting exhaust gases passing therethrough to the ends of the housing and into the space between the case and housing, the case having an exhaust port leading therefrom at a point intermediate the ends of the housing, a further exhaust port leading therefrom in alignment with one end of the housing and means for regulating the effective openings of said exhaust ports.

3. In rotary valve mechanism for internal combustion engines, a case, a housing within and supported from and in spaced relation to the case, a valve rotatable in the housing having intake and exhaust ports, connections between the exhaust ports conducting exhaust gases passing therethrough to the ends of the housing and into the space be-

tween the case and housing, the case having an exhaust port leading therefrom at a point intermediate the ends of the housing, and further exhaust ports leading therefrom at the ends thereof.

4. In rotary valve mechanism for internal combustion engines, a case, a housing within and supported from and in spaced relation to the case, a valve rotatable in the housing having intake and exhaust ports, connections between the exhaust ports conducting exhaust gases passing therethrough to the ends of the housing and into the space between the case and housing, the case having an exhaust port leading therefrom at a point intermediate the ends of the housing, further exhaust ports leading therefrom at the ends thereof, and means for controlling the effective area of said exhaust ports.

5. In rotary valve mechanism for internal combustion engines, a case, a housing within and supported from and in spaced relation to the case, a valve rotatable in the housing having intake and exhaust ports, connections between the exhaust ports conducting exhaust gases passing therethrough to the ends of the housing and into the space between the case and housing, the case having an exhaust port leading therefrom at

a point intermediate the ends of the housing, the connections between said exhaust ports including a pair of conduits arranged within the valve and having their walls in spaced relation thereto and means for conducting incoming fuel about said conduits to said intake ports.

6. In rotary valve mechanism for internal combustion engines, a case, a housing within and supported from and in spaced relation to the case, a valve rotatable in the housing having intake and exhaust ports, connections between the exhaust ports conducting exhaust gases passing therethrough to the ends of the housing and into the space between the case and housing, the case having an exhaust port leading therefrom at a point intermediate the ends of the housing, the connections between said exhaust ports including a pair of conduits arranged within the valve and having their walls in spaced relation thereto and means for conducting incoming fuel about said conduits to said intake ports, each of said conduits communicating at its inner end with one of exhaust ports lying at opposite sides of the transverse medial line of the valve and at its opposite end opening at an end of the valve.

ALBAN W. ANDERSON.
